UNITED STATES PATENT OFFICE

OTTO RIEHMANN, OF WELLINGSBUTTEL, GERMANY

PRESS

Application filed September 11, 1928, Serial No. 305,224, and in Germany March 22, 1928.

The present invention relates to an improved power-driven press for expressing juice or fluid from compressible substances of vegetable origin such as are employed in the 5 production of starch, but the press may also be employed to advantage for expressing oil from seeds, nuts and other oleaginous substances and for draining peat and the like.

More particularly the invention relates to 10 presses of that kind which consist of a cylinder in connection with a feed hopper and a perforated tapered discharge channel at the exit end of the cylinder, the piston or plunger reciprocating inside the cylinder being driven by a crank mechanism.

In presses of this kind the piston or plunger at the termination of the working stroke of the crank mechanism is reciprocated i. e. changed in its direction of motion without 20 delay, so that the maximum pressure is exerted only momentarily, the reaction of the substance under treatment tending to force the piston or plunger back.

According to the present invention the efficiency of such presses is materially increased by maintaining the maximum pressure and even augmenting said pressure at the termination of the working stroke of the 25 crank mechanism.

With this end in view the invention consists in the novel combination, arrangement and adaptation of parts, all as more fully hereinafter described, shown in the accompanying drawing and then specifically set out 30 in the appended claims.

In the drawings

Fig. 1 is a diagrammatic side elevation partly in vertical section, of the improved press with the crank mechanism for reciprocating the piston or plunger.

Fig. 2 is a partial horizontal section of the piston or plunger of the press with the crank mechanism for reciprocating same in the position it assumes at the termination of the 45 working stroke.

Fig. 3 is a partial horizontal section of the piston or plunger of the press with the crank mechanism for reciprocating same in the position it assumes at the moment of changing the direction of motion of the piston or plunger when the working stroke of same is completed.

The horizontal or slightly inclined cylinder *a* of the press is in connection with the feed hopper *b* and with the perforated tapered discharge channel *c*, which is closed at its free extremity by means of an oscillatory suspended lid *c*'.

The piston or plunger *d* reciprocating inside the cylinder *a* serves for acting upon the substance supplied to the cylinder by way of the feed hopper *b*, the piston or plunger forcibly pushing said substance towards and into the perforated tapered discharge channel *c*.

The piston or plunger *d* is reciprocated by means of an improved crank mechanism. Instead of a pitman rod linking the piston or plunger positively to the crank, a loose connection of special construction is provided. The piston or plunger *d* carries perpendicularly in regard to its direction of motion a set of push bars *e* and *f* spaced apart a distance in excess to that of the stroke of the piston or plunger and rigidly connected together by means of the stay bolts *g* and *h* at or near their extremities. It is advisable to employ two sets of push bars *e* and *f* each forming a rigid frame in symmetrical arrangement at both sides of the longitudinal axis of the piston or plunger as indicated in Fig. 2.

The space enclosed between the push bars *e* and *f* and their stay bolts *g* and *h* serves for accommodating the crank shaft *i* transversely in regard to the cylinder *a*. Fixed to the shaft *i* in symmetrical arrangement are two crank arms *j*, *j* each provided with a roller *k* at its extremity adapted to bear against the push bars *e*, *e* and *f*, *f* for moving

the piston or plunger *d* to and fro inside the cylinder *a*.

The crank mechanism so far described stops driving the piston or plunger *d* when the crank arms *j*, *j* in one or the other direction acting against the push bars *e* or *f* reach and pass a line coincident with or parallel in regard to the longitudinal axis of the cylinder *a* and piston *d*. While the crank arms *j*, *j* perform the inactive part of their rotation the piston or plunger *d* retains its position when the cylinder *a* is charged from the hopper *b*; at the termination of its working stroke, however, the piston or plunger does not retain its position owing to the reaction of the substance under pressure tending to force the piston back. This is disadvantageous because it decreases the working effect of the press.

To obtain the highest working effect of the press by maintaining the maximum pressure and even augmenting said pressure of the piston at the termination of the working stroke of the crank mechanism, a cam *l* is fixed to the piston *d* between the push bars *e*, said cam being formed with a circular race for an auxiliary roller *m* which is carried by the secondary crank arms *n*, as shown in Fig. 3.

The circular race of the cam *l* is fixed eccentric in regard to the crank shaft *i* and the roller *m* follows the rollers *k* at such a distance that it starts acting when the rollers *k* have completed their action, as indicated in Fig. 1.

When the crank shaft *i* continues its rotation in the direction of the arrow, the roller *m* acts against the circular race of the cam *l*. Owing to the eccentricity of the circular race the cam *l* and with it the piston or plunger *d* are pushed forward some distance indicated in Fig. 1 by the dotted line parallel in regard to the circular race of the cam. This supplementary actuation of the piston or plunger obtains and maintains the maximum pressure until the moment the piston or plunger starts its return journey for recharging the cylinder *a*.

It must be observed here, that the reduction in volume of the substance under pressure due to the expression of the liquid therefore diminishes the action of the press if the piston or plunger is only held stationary in the position it assumes at the termination of the working stroke of the crank mechanism.

The return journey of the piston or plunger *d* for recharging the cylinder *a* is started when the roller *m* has completed its travel along the circular race of the cam *l*. In Fig. 1 the dotted circles *k*¹, *m*¹ indicate the relative positions of the rollers *k* and *m*, at the moment when the roller *m* is about to disengage from the cam *l* and when the rollers *k* are about to contact with the push bars *f*. In

the same figure the dotted circles *k*², *m*² indicate the relative positions of the rollers *k* and *m* at the moment when the rollers *k* have completed their action against the push bars *f* and in company with same have moved the piston or plunger *d* into its inoperative position for recharging the cylinder *a*.

Guide rails *o* on the bed plate *p* of the press are engaged by the feet of the push bars *e* and *f* so as to rectilinearly guide the latter in their to and fro motion.

The liquid expressed from the substance charged into the cylinder *a* escapes through the perforations in the circumferential wall of the discharge channel *c* and through the perforations in the head of the hollow piston or plunger *d*, arrows indicating in Fig. 1 the course of the liquid through the hollow piston or plunger and along inclined gutters *q*, *r* below the cylinder *a* which receive the liquid from the latter at the rear end of same. The gutter *q* moves to and fro with the piston or plunger *d*, being attached thereto; the gutter *r* is fixed in the base *s* of the press below the gutter *q*. The liquid is discharged from the gutter *r* into a receiver *t* which is in connection with the perforated discharge channel *c* of the cylinder *a* as shown in Fig. 1, a conduit *u* leading the liquid from the receiver *t* to its place of destination.

The compressed substance after leaving the cylinder *a* reaches the perforated discharge channel *c* collecting therein and filling same until it opens the lid *c*¹ and finds its way out.

While I have shown in the accompanying drawing the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims, or of mechanical equivalents to the structure set forth.

What I do claim as my invention and desire to secure by Letters Patent is:

1. An apparatus for expressing juice or fluid from compressible substances, comprising a cylinder, a feed hopper communicating with said cylinder, a perforated, tapered discharge channel at one end of the cylinder, a piston in said cylinder, an open frame carried by the piston outside the cylinder, a rigidly supported shaft passing through the opening in said frame, a crank on said shaft co-operating with the frame members for reciprocating the piston within the cylinder, a cam element carried by said frame between the shaft and the piston, and an additional crank on the shaft adapted to engage said cam element so as to support the

piston against the reaction of the compressed materials after the first crank has passed its dead centre position.

2. A structure as claimed in claim 1 where-
in the cam element is adapted to remain in engagement with the additional crank until the first crank is ready to retract the piston, said cam element being eccentric relative to the shaft and adapted to effect a gradual 10 advance of the piston.

In witness whereof I have hereunto signed my name this 28th day of August 1928.

OTTO RIEMANN.
